United States Patent

Des. 240,648
Patented July 20, 1976

240,648

MACHINE FOR PROCESSING CROP STACKS

Allen Andrew White, Peabody, and Ray Addison Ade, Ronald Henry Knopp, and Bruce Lynn White, Newton, Kans., assignors to Hesston Corporation, Hesston, Kans.

Filed Dec. 19, 1974, Ser. No. 534,909

Term of patent 14 years

Int. Cl. D15—03

U.S. Cl. D40—1 E

Fig. 4.

Fig. 3.

FIG. 1 is a perspective view of a machine for processing crop stacks pursuant to our present design showing the top, front and left side thereof;

FIG. 2 is a perspective view showing the top, rear and right side thereof;

FIG. 3 is a perspective view showing the left side thereof;

FIG. 4 is a front perspective view thereof;

FIG. 5 is a perspective view showing the right side thereof; and

FIG. 6 is a rear perspective view thereof.

We claim:

The ornamental design for a machine for processing crop stacks, as shown.
